UNITED STATES PATENT OFFICE.

ALBERT E. KAY, OF LOWELL, MASSACHUSETTS, ASSIGNOR TO DRAPER CORPORATION, OF HOPEDALE, MASSACHUSETTS, A CORPORATION OF MAINE.

BUILDER MECHANISM FOR WINDING MACHINES.

Application filed November 14, 1922. Serial No. 600,847.

To all whom it may concern:

Be it known that I, ALBERT E. KAY, a citizen of the United States, and a resident of Lowell, in the county of Middlesex and State of Massachusetts, have invented an Improvement in Builder Mechanisms for Winding Machines, of which the following description, in connection with the accompanying drawings, is a specification, like characters on the drawings representing like parts.

This invention relates to builder mechanisms for winding a supply of yarn upon yarn receivers.

It is now the general practice to wind yarn upon yarn receivers, such as bobbins or the like, by providing a preliminary wind in the form of a bunch and then completing the windings by a regular service traverse. The preliminary windings or bunch have heretofore been wound upon the yarn receivers by traversing the yarn lengthwise of the receivers with a short traverse which is gradually increased and merges into the regular service or longer traverse for completing the windings upon the yarn receivers. In other cases the preliminary windings have been wound upon the yarn receivers with a short traverse without gradual increase thereof, in order to form a distinct bunch, and then a regular service traverse has been inaugurated to complete the windings.

The present invention is more especially directed to that type of builder mechanisms which build the bunch with a relatively short traverse, and then pass at once into the longer or regular service traverse, and is more especially a further development of the builder mechanism shown and described in the patent to Jonas Northrop, No. 882,793, dated March 24, 1908.

In the Northrop patent to which reference has been made the preliminary windings are placed upon the yarn receivers with a gradually increasing traverse which merges into the longer service traverse, and one of the features of the present invention consists in a builder mechanism of the general type of that of the Northrop patent modified or restricted, however, to permit the building of a bunch with a relatively short traverse and upon the completion of such bunch with a

short traverse to pass at once into the longer service traverse to complete the windings of 55 yarn on the yarn receivers.

In the drawings:

Fig. 1 is a perspective view of portions of a winding or spinning machine with the present invention applied thereto; 60

Fig. 2 is an enlarged perspective detail showing more particularly the segment governor holding the segment in bunch building position;

Fig. 3 is a view similar to that of Fig. 2 65 but showing the segment governor in the position it occupies when the bunch is completed;

Fig. 4 is a plan view showing the segment governor and the parts associated therewith; 70

Fig. 5 is a side elevation, parts in section, showing the bunch builder segment in bunch building position.

The bunch builder mechanism as shown 75 in the present instance, is applied to a spinning machine in which a ring rail constitutes the yarn guiding means for directing the yarns upon the yarn receivers, but it will be understood of course that the present invention is not restricted thereto, but on the contrary may be employed in connection with various types of winding and spinning machines.

Referring more particularly to Fig. 1, the 85 machine frame 1 may be of usual character for supporting the operating parts and between the end portions of the main frame is a bar 2 provided with brackets 3 for the support of the rock shaft 4 which is normally 90

under the influence of a weight 5 tending to turn the rock shaft in a clockwise direction, Fig. 1. Secured to the rock shaft 4 is the arm 6 carrying a pin or roll 7 on which rests the shoe 8 of the ring rail controlling rod 95

9. The ring rail 10 is provided with the usual rings and travelers 11 and the yarn carriers on which the yarn is wound are mounted upon the spindle rail 12 and extend upwardly through the rings on the ring 100 rail. These parts are of usual construction, and while only one yarn carrier and ring is shown, it is to be understood of course that there will or may be a plurality of such parts.

Secured to the rock shaft 4 is the arm 13

by means of which and the weight 5 the ring rail is given its traversing movement from the builder mechanism. These parts may be substantially the same as in the Northrop 5 patent.

- Pivottally mounted on the stud or dead shaft 14 supported by the machine frame is the builder arm 15 which carries the usual worm 16 and pick wheel 17 both of which 10 are connected to the shaft 18. The pick wheel is given a step by step feed movement as usual through the pawl and ratchet mechanism usual in this class of devices. The builder arm carries a roll or pin 19 which 15 engages the builder cam 20 receiving rotative movement from a going part of the machine, and the pin or roll 19 is held in contact with the cam by the usual weight 21. These parts are of usual construction.
- 20 Secured to the machine frame is the bracket 22 having arms 23 between which extends the pin or stud 24. The pin or stud 24 serves as the axial support for the drums 25 and 26 which receive movement from the 25 builder arm by the usual connection or chain 27 secured to one of the drums.

One of the drums 26 is connected to the arm 13 by the regular traverse connection or chain 28, the construction being such that 30 as the builder arm is rocked by the builder cam the ring rail will receive traverse movement lengthwise of the yarn carriers.

Loosely mounted upon the stud or shaft 24 is the bunch building segment 29 having 35 a pin or roll 30 and a rest 31 over which passes the bunch builder chain or connection 32 the end portion 33 of which is secured to the disk 34 in one of the holes 35 provided for such purpose. The bunch building chain 40 32 has its other end connected to the arm 13 at 35. The parts so far described, with the exception of the plurality of holes 35 in the disk 34 for the connection of the builder chain, may be substantially the same as set 45 forth in the patent to Northrop hereinbefore mentioned.

The bracket 22 carries an upper bearing surface or portion 36 provided with a guideway for a slotted link or member 37 which 50 is connected to the bunch building segment at 38.

Mounted upon the bracket 32 is the segment governor 39 having an end or finger portion 40 and the segment governor 39 55 passes through the slot 41 of the link 37. The segment governor 39 is confined to sliding movement on the support 36 by guides 42 and when in its operative position or starting to build the bunch the finger or 60 projection 40 of the segment governor is within the slot 41 of the link 37 and holds the bunch building segment in operative position during the building of the bunch. When, however, the bunch has been completed with the short traverse dictated by the 65

bunch building segment and the connection 70 32 to the yarn guiding means, the bunch building segment governor 39 is disengaged from the link 37, thereby entirely freeing the segment 29 which thereafter has no further function during the completion of the 75 yarn carrier winds.

The segment governor is controlled from means on the builder arm, so that when the bunch is completed the controlling means 75 effects movement of the governor into its inoperative position, as indicated in Fig. 3, whereupon the longer regular traverse of the 80 yarn guides is initiated.

The governor controlling means in the 80 present instance comprises the rocking arm 43 pivoted at 44 and connected to the segment governor by a rod 45. The lower end portion of the rocking arm 43 is connected at 46 to a rod 47 one end of which is secured at 48 to a toothed rack 49 the teeth of which engage the worm 16, the construction being such that as the pick wheel is rotated step by step during the bunch 90 building operation, the rack 49 will be moved rearwardly until when the bunch is completed the segment governor 39 will be disengaged from the slot 41 of the link 37 to permit the bunch building segment 29 to move to inoperative position, as indicated in Fig. 3, thereby jumping at once from the bunch building short traverse to the 95 longer service traverse.

It is desirable in some instances to bevel the end portions of the finger 40 as at 50 and 100 to reversely bevel the end wall of the slot 41 as at 51 to insure the entrance of the finger 40 of the governor into the slot when the bunch builder is wound back to starting position.

When the winding has been completed it is usual in builder mechanisms to wind back the parts into starting position and the present invention provides means for returning the bunch building segment 29 to its 110 bunch building position at such time.

In the present instance, a spring 52 has one end secured at 53 to the bunch building segment 29 and its other end secured to a fixed point at 54, the construction being 115 such that when the building mechanism is run back to starting position, as usual in this class of machines, and the rack 49 moves forwardly, the segment 29 will be moved counter clockwise from the position indicated in Fig. 3 to that indicated in Fig. 2, thereby positioning the slot 41 of the link 37 for the entrance of the finger 40 of the segment governor, so that the bunch building elements assume their starting position automatically for building the bunch.

From the construction described it will be apparent that in accordance with the present invention the bunch on the yarn carrier is built with a short traverse and when the 130

bunch is completed by such short traverse, the segment governor is moved to disengage the finger 40 from the slot in the link 41 so that the bunch building segment may at 5 once move to an inoperative position to permit the longer regular traverse for completing the windings on the carriers to start at once without merging the traverse of the bunch into the regular traverse.

10. What is claimed is:

1. In a builder mechanism for winding machines, the combination of the builder arm and builder cam, means for guiding the yarn to yarn receivers, connections between 15 the builder arm and said means for traversing the latter, including a bunch building segment, a segment governor mounted for sliding movement independent of the segment, and segment governor controlling means for 20 sliding the segment governor to operative position for traversing the yarn guiding means with a short traverse until the bunch is completed with such short traverse and then sliding the segment 25 governor to an inoperative position to cause the bunch building segment to become at once ineffective that the windings on the yarn receivers may continue with regular service traverse.

30. 2. In a builder mechanism for winding machines, the combination of the builder arm and builder cam, means for guiding the yarn to yarn receivers, connections between the builder arm and said means for 35 traversing the latter, including a bunch building segment, a segment governor mounted independent of the segment and including a sliding finger, and segment governor controlling means for moving the sliding 40 finger to bunch building position for traversing the yarn guiding means with a short traverse until the bunch is completed with such short traverse and then sliding the finger at once out of operative position 45 that the windings on the yarn receivers may continue with regular service traverse, and yielding means acting upon the bunch building segment to automatically return it to bunch building position when the builder 50 mechanism is returned to starting position.

55. 3. In a bunch building mechanism for winding yarn upon yarn receivers, the combination of yarn guiding means for delivering yarn to the yarn receivers, a builder arm and builder cam, and connections between the builder arm and yarn guiding means, including a bunch building segment, a segment governor mounted for sliding movement and having a laterally extended 60 bunch building finger constructed and arranged to cause the bunch building segment to traverse the yarn guiding means with a short traverse during the building of the entire bunch, and segment governor controlling means for sliding the segment 65

governor and the bunch building finger to an inoperative position as soon as the bunch has been completed with the short traverse that the windings on the yarn receivers may continue with the longer service traverse. 70

4. In a builder mechanism for winding yarn upon yarn receivers, the combination of yarn guiding means for delivering yarn to the yarn receivers, a builder arm and builder cam, and connections between the 75 builder arm and yarn guiding means, including a bunch building segment, a segment governor mounted for movement independent of the segment and having a finger for holding the segment in position to wind 80 and complete the bunch with a shorter traverse than the regular service traverse, and segment governor controlling means for automatically throwing the governor and finger out of operative position as soon as 85 the bunch has been completed with the short traverse that the full regular service traverse may start at once.

5. In a builder mechanism for winding yarn upon yarn receivers, the combination 90 of yarn guiding means for delivering yarn to the yarn receivers, a builder arm and builder cam, and connections between the builder arm and yarn guiding means, including a bunch building segment, an independently mounted segment governor, having a portion for holding the segment in position to wind and complete the bunch with a shorter traverse than the regular service traverse, and segment governor controlling means for automatically moving the governor relative to the segment out of operative position as soon as the bunch has 95 been completed with the short traverse that the full regular service traverse may start 100 at once, and a spring acting on the segment to move it relative to the segment governor to operative position for building the bunch when the builder mechanism is returned to starting position. 105

6. A builder mechanism, comprising, in its construction, a builder arm and builder cam, guiding means for directing yarn to yarn receivers, connections between the builder arm and yarn guiding means, including a bunch building segment, a segment governor formed as a slide having a finger for holding the bunch building segment in position to build the bunch with a short traverse, and means for moving the 115 finger out of operative position when the bunch has been completed with a short traverse that the longer service traverse may be effected at once.

7. A builder mechanism, comprising, in 120 its construction, a builder arm and builder cam, guiding means for directing yarn to yarn receivers, connections between the builder arm and yarn guiding means, including a bunch building segment, a seg- 125

4
ment governor formed as a slide having a finger for holding the bunch building segment in position to build the bunch with a short traverse, and means for moving the finger out of operative position when the bunch has been completed with a short traverse that the longer service traverse may be effected at once, and a spring for returning the segment to bunch building position when the builder mechanism is returned to starting position.

8. A builder mechanism, comprising, in combination, a builder arm, a builder cam, a ring rail and connections between the builder arm and ring rail including a bunch building segment, a segment governor formed as a slide having a finger extending at an angle thereto for holding the segment in bunch building position until the bunch is completed with a short traverse and then releasing the segment from its operative

position that the longer service traverse may start at once.

9. A builder mechanism, comprising, in combination, a builder arm, a builder cam, 25 a ring rail and connections between the builder arm and ring rail including a bunch building segment, a segment governor formed as a slide having a finger extending at an angle thereto for holding the segment 30 in bunch building position until the bunch is completed with a short traverse and then releasing the segment from its operative position that the longer service traverse may start at once, and a spring acting to 35 automatically return the segment to bunch building position when the builder mechanism is returned to bunch building position.

In testimony whereof, I have signed my 40 name to this specification.

ALBERT E. KAY.
